T. B. SLATE

QUICK SEALING CLOSURE FOR REFRIGERATING DEVICES

Original Filed Jan. 10, 1924

Inventor
Thomas B. Slate

By *Lester L. Sargent*

Attorney

UNITED STATES PATENT OFFICE.

THOMAS B. SLATE, OF NEW YORK, N. Y.

QUICK-SEALING CLOSURE FOR REFRIGERATING DEVICES.

Original application filed January 10, 1924, Serial No. 685,482. Divided and this application filed April 10, 1924. Serial No. 705,595.

To all whom it may concern:

Be it known that I, THOMAS B. SLATE, a citizen of the United States, residing at New York, in the county of New York and State 5 of New York, have invented a new and useful Quick-Sealing Closure for Refrigerating Devices, of which the following is a specification.

This application is a division of my allowed application, Serial No. 685,482, filed January 10, 1924, now Patent Number 1,511,306, granted October 14, 1924.

My object is to provide a novel quick sealing closure which can be quickly applied to and removed from a container to permit formation and removal of a cake of carbon dioxide snow; and to provide means for effecting an automatic seal of such a container against high pressure exerted from 20 within on the closure while said cage of snow is being formed within the container. I attain the objects of my invention by the device illustrated in the accompanying drawings, in which—

25 Figure 1 is a vertical section through my invention, the container being shown partly in elevation;

Fig. 2 is a detail perspective view of the lower end of the refrigerator shell or container 8;

Fig. 3 is a detail perspective view of detachable flange ring 10;

Fig. 4 is a detail side elevation of removable end wall 12; and

35 Fig. 5 is a detail sectional view of resilient ring 13.

Like characters of reference designate like parts in each of the several views.

Referring to the accompanying drawings, 40 I provide a suitable refrigerator shell or container 8 for liquid carbon dioxide under high pressure, the numeral 14 designating the carbon dioxide snow, which as described in said application is in the form of a more or less porous cake. The bottom of the container 8 is a closure plug 12, supported by quick-detachable flange collar 10 and interposed resilient ring 13. Flange collar 10 and shell or container 8 are threaded in a similar 45 manner, preferably at spaced portions, permitting of quick application or removal of the flange ring 10 and closure 12. Pressure from within the container on closure 12 and thus on the interposed resilient ring 13

causes the latter to automatically effect a 55 tight seal of the container.

It will be noted that the container 8 is of approximately uniform cross-section and that the removable bottom closure fits the lower end thereof loosely so that its removal 60 leaves the bottom open to the maximum cross-section of the cake 14, affording a free exit for the entire cake. By having the bottom closure in the form of a piston-like head with a cylindrical downward extension 65 fitting the flange collar opening as shown, and by having the resilient ring 13 substantially the proper diameter to loosely fit the interspace, it will be evident that when great downward pressure is applied the radial inward and outward expansion of material of the ring seals the joint radially of the container in addition to the seal afforded by the direct squeezing of the ring by pressure taking effect lengthwise of the container. 70

Whenever desired, the flange ring 10 may be easily turned to the left until the threaded portions 11 of the flange ring and container disengage each other through the vacant 80 spaces and the flange ring is readily and quickly slipped off, allowing the contents of container 8 to fall into any convenient receptacle. The bottom closure is then replaced by pushing it back to position and 85 turning it to the right until the threaded portions 11 properly engage each other.

What I claim is:

1. In apparatus of the class described, a container for cake material of uniform 90 cross-section open at one end thereof, said container having its open end provided with spaced threaded portions, a flange ring having corresponding spaced threaded portions adapted for quick removal and replacement 95 on the open end of the said container, a closure having an area substantially equal to the maximum cross-section of the container and slidably seated within the open end of said container, and an elastic ring interposed 100 between the closure and the inturned flange of the flange collar to effect an air-tight joint when pressure is exerted on the closure from within the container.

2. In apparatus of the class described, a 105 container for cake material of uniform cross-section open at one end thereof, said container having its open end provided with

spaced threaded portions, a flange ring having corresponding spaced threaded portions adapted for quick removal and replacement on the open end of the said container, a closure having an area substantially equal to the maximum cross-section of the container and slidably seated within the open end of said container, and an elastic ring interposed between the closure and the inturned flange ¹⁵ of the flange collar to effect an air-tight joint

when pressure is exerted on the closure from within the container, said closure being formed with a reduced cylindrical extension approximately fitting and extending through the opening afforded by the flange collar and said elastic ring being of proper cross-section to spread and seal the joint radially as well as lengthwise of the container.

THOMAS B. SLATE.
